UNITED STATES PATENT OFFICE.

J. WILLARD GROVES, OF BARNESVILLE, OHIO, ASSIGNOR TO THE LOTUS CUT GLASS CO., OF BARNESVILLE, OHIO.

DESIGN FOR THE SURFACE ORNAMENTATION FOR A GLASS GOBLET OR SIMILAR ARTICLE.

59,077.

Specification for Design. Patented Sept. 20, 1921.

Application filed March 17, 1921. Serial No. 453,152. Term of patent 3½ years.

To all whom it may concern:

Be it known that I, J. WILLARD GROVES, a citizen of the United States, residing at Barnesville, in the county of Belmont and State of Ohio, have invented a new, original, and ornamental Design for the Surface Ornamentation for a Glass Goblet or Similar Article, of which the following is a specification, reference being had to the accompanying drawing, forming part thereof.

Figures 1 and 2 are side elevations of a glass goblet or similar article showing my design, said elevations being taken at right angles to each other.

I claim:

The ornamental design for the surface ornamentation for a glass goblet or similar article, as shown.

J. WILLARD GROVES.
